[57] CLAIM

The ornamental design for a playing piece for game, substantially as shown and described.

DESCRIPTION

FIG. 1 is a perspective view of a playing piece for a game showing my new design;

FIG. 2 is a top plan view;

FIG. 3 is a side elevation view, looking directly at a flat side of the upper portion of the playing piece; and

FIG. 4 is another side elevational view, looking directly at a corner of the upper portion of the playing piece.

The bottom of the playing piece is not shown since it is simply a flat circular surface.
